CLAIM

The ornamental design for a double CD rack, as shown and described.

DESCRIPTION

FIG. 1 is a front, right perspective view of a double CD rack showing my new design.

FIG. 2 is a front, plan view of the double CD rack of FIG. 1.

FIG. 3 is a right side view of the double CD rack of FIG. 1.

FIG. 4 is a left side view of the double CD rack of FIG. 1.

FIG. 5 is a top view of the double CD rack of FIG. 1.

FIG. 6 is a back plan view of the double CD rack of FIG. 1; and,

FIG. 7 is a bottom view of the double CD rack of FIG. 1. The broken line showings throughout the views are for illustrative purposes only and form no part of the claimed design.
